(57) **CLAIM**

The ornamental design for a display screen or portion thereof with transitional graphical user interface, as shown and described.

DESCRIPTION

FIG. 1 is the first image in a sequence for a display screen or portion thereof with transitional graphical user interface, showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof; and,

FIG. 7 is the seventh image thereof.

The outermost broken line rectangle around FIGS. 1-7 show a display screen or portion thereof and form no part of the claimed design. The remaining broken lines show portions of the graphical user interface that form no part of the claimed design.

The subject matter in this patent includes a process or period in which an image changes into another image. This process or period forms no part of the claimed design.
